UNITED STATES PATENT OFFICE.

MELVIN E. KROTZER, OF PEMBerville, OHIO.

BOOT-ROBE.

1,302,179.

Specification of Letters Patent. Patented Apr. 29, 1919.

Application filed April 24, 1918. Serial No. 230,546.

To all whom it may concern:

Be it known that I, MELVIN E. KROTZER, a citizen of the United States, residing at Pemberville, in the county of Wood, State of Ohio, have invented certain new and useful Improvements in Boot-Robes; and I do hereby declare the following to be a full, clear, and exact description of the invention, such as will enable others skilled in the art to 10 which it appertains to make and use the same.

The invention relates to a lap robe, and more particularly to the class of combination laprobes and boot coverers adapted for use 15 in vehicles, automobiles or the like.

The primary object of the invention is the provision of a robe of this character wherein it has thereon boot coverers, one being permanently a part thereof and the other 20 detachable so that it can be interchanged from one side to the other of the robe, thus enabling the robe to be used when operating an automobile with a right or left hand pedal, and the user of the robe can place 25 either one or both feet within the coverers, the latter being of a size to wholly receive the feet of the user of the robe and are disposed in such a manner as to permit the said robe to be wrapped tightly about the limbs 30 or the lower body portion of the user without possibility of the cold air entering through the robe, it thereby protecting said user from the cold air about the feet or legs.

Another object of the invention is the provision of a robe of this character wherein the feet coverers are in the form of flexible boots so that the feet of the user of the robe are wholly confined therein and may be manipulated for operating the foot pedals of 40 an automobile without unduly disarranging the robe when wrapped about the person or causing the robe to become unwrapped in the use of the feet in this manner.

A further object of the invention is the 45 provision of a robe of this character wherein the lower portion of the body of the user thereof can be properly covered to exclude cold air, thereby assuring warmth to the user of the robe.

With these and other objects in view, the 50 invention consists in the features of construction, combination and arrangement of parts as will be hereinafter fully described, illustrated in the accompanying drawing, 55 and pointed out in the claims hereunto appended.

In the accompanying drawing:

Figure 1 is a perspective view of a robe 60 constructed in accordance with the invention;

Fig. 2 is an edge elevation of the robe showing one of the coverers at one side and the other coverer at the opposite side;

Fig. 3 is a vertical sectional elevation;

Fig. 4 is a fragmentary side elevation of 65 the robe and boot coverers, the robe being wrapped about the legs of the operator and the boots on the feet of the operator within the boot coverers, a portion of the robe being broken away.

Similar reference characters indicate corresponding parts throughout the several views in the drawing.

Referring to the drawing in detail, A designates generally a lap robe of the usual 75 rectangular shape, although the same may be of any desired shape, and in this instance being made from a double ply textile fabric, yet the same may be made from any other suitable material and of any number of plies 80 thereof.

Formed spaced from the bottom edge and contiguous to one end edge of said robe A is a pair of spaced openings 5, preferably of oval shape, and having their lengths disposed in the direction of the bottom and top edges of the robes. Stitched or otherwise secured permanently to the robe A at one side thereof about the edge of one of the 85 openings 5 is a flexible boot coverer in the 90 form of a boot 6, preferably made from material corresponding to the material of the robe, and communication is had to the interior thereof through the opening 5 for the reception of one foot of the user of the 95 robe, the bottom of the boot 6 being provided with a leather sole 7, although this sole may be made from other material.

On opposite sides of the robe A about the edge of the other opening 5 are suitable 100 male members 8 of snap fasteners, the female members 9 of which are mounted at the edge of the open end of the leg portion 10 on a detachable boot covered in the form of a boot 11 which is made correspondingly 105 to the boot 6 and having the leather sole 12 which may also be made from any other material. The detachable boot 11 can be worn on the robe at either side thereof.

The detachable boot 11 permits the use 110 of the robe by a right or left hand driver, or that it may be used in an automobile

either of the right or left hand driving type.

When the boots 6 and 11 are located on one side of the robe A the latter will be 5 adaptable for use by a single person and both feet of the user can be inserted in the boots 6 and 11 through the openings 5, the boots being of a size to wholly receive the 10 footwear covering the foot of the user of the robe and the flexibility of these boots will permit limited movement of the feet of the user as will be apparent. In the individual 15 use of the robe the shoe covered feet of the user are inserted within the boots 6 and 11 and thereafter the robe A is wrapped about the legs and the lower portion of the 20 body of the user, so that the body portion, legs and feet of the user will be completely wrapped to exclude cold air and thereby assuring warmth when the robe is in use.

Now if the robe is to cover the operator of an automobile either of the left or right hand driving type and another person, the boot 11 is adjusted to either side of the robe 25 accordingly to the position of the driver so that his foot may be placed within the boot 10 for operating the foot pedal in the automobile, thus the robe being interchangeable to suit a right or left hand driver as the 30 occasion may require, it being seen that when the driver is at the left hand side of the automobile both feet may be placed within the boots and on the adjustment of the boot 11 for a right hand driver but one 35 of the feet can be placed within a boot coverer, namely, the right hand foot.

From the foregoing it is thought that the

construction and manner of use of the robe will be clearly understood, and therefore a more extended explanation has been omitted. 40

It is of course to be understood that the boots 6 and 7 are properly reinforced to prevent the collapsing thereof and to enable the feet to be inserted therein and withdrawn therefrom; also having suitable 45 straps connected to the soles and to the top of said boots to avoid sagging while the robe at the point of the opening for the detachable boot may be provided with a flap to close said opening when the detachable 50 boot is removed from the robe.

What is claimed is:

1. The combination with a lap robe provided with an aperture near one lower corner thereof, of flexible boot shaped foot 55 coverers adapted for detachable connection with the robe at either side thereof about the edge of the aperture therein.

2. The combination with a lap robe provided with a pair of apertures located at 60 one lower corner thereof, of flexible boot shaped foot coverers, one of the boot coverers being permanently fixed about the edge of one of the apertures to project from one side of the robe, and means for detachably 65 fastening the other boot coverer on either side of the robe about the edge of the other aperture.

In testimony whereof, I affix my signature, in the presence of two witnesses.

MELVIN E. KROTZER.
